(57) **CLAIM**

The ornamental design for an apparatus for vacuum packing, as shown and described.

DESCRIPTION

FIG. 1 is a bottom-rear perspective view of an embodiment of an apparatus for vacuum packing, showing my new design;

FIG. 2 is a bottom-front perspective view thereof;

FIG. 3 is a rear view thereof;

FIG. 4 is a front view thereof;

FIG. 5 is a right side elevation view thereof, the left side elevation view being a mirror image of the left side;

FIG. 6 is a top view thereof; and,

FIG. 7 is a bottom view thereof.
